(57) CLAIM

The ornamental design for a golf club head, as shown and described.

DESCRIPTION

FIG. 1 is a first perspective photographic view of the second a golf club head showing our new design;

FIG. 2 is a rear photographic view thereof;

FIG. 3 is a second perspective photographic view thereof;

FIG. 4 is a front photographic view thereof;

FIG. 5 is a heel end photographic view thereof;

FIG. 6 is a toe end photographic view thereof;

FIG. 7 is a top photographic view thereof; and

FIG. 8 is a bottom photographic view thereof.

The broken line showing of various aspects of the golf club head, including the unshaded regions therein, is for illustrative purposes only and forms no part of the claimed design.
